UNITED STATES PATENT OFFICE.

GEORGE E. MONROE, OF DETROIT, MICHIGAN.

NUT LOCK.

Application filed December 6, 1924. Serial No. 754,297.

To all whom it may concern:

Be it known that I, GEORGE E. MONROE, a citizen of the United States, residing at Detroit, in the county of Wayne and State 5 of Michigan, have invented a new and useful Improvement in Nut Locks, of which the following is a specification.

This invention is in part an improvement on the subject matter of my pending application improvements in nut locks Serial Number 693,696, filed February 18th, 1924. In both inventions the construction is somewhat similar in that an upper flat plate and a companion plate having flexed extensions 15 are used in combination, but in the prior application aforesaid the two plates are firmly united at their margins, whereas in the present invention the companion plate is provided with a transverse groove arranged 20 substantially centrally of the said plate, and the sides of the groove have bevelled guides adapted to receive similarly bevelled edges of a downwardly projecting portion on the underside of the top plate.

One of the objects of the present invention is to simplify the method of manufacture while at the same time providing a nut lock that will be quite as positive in action; and another object of the invention 25 is to provide a depressed portion of the companion plate centrally of the nut lock which will form a positive stop and prevent the flexed extensions of the said companion plate from being flattened out entirely when 30 subjected to excessive pressure.

With these and other objects in view my invention consists in certain novel method of construction and combination of parts 35 hereinafter more fully described with the aid of the accompanying drawings and claimed.

Figure 1 illustrates a plan view, and

Figure 2 a side elevation of the nut lock when applied.

Figure 3 is a blank form from which an embodiment of the top plate is made.

Figure 4 shows a side elevation of a top plate when ready for assembly.

Figure 5 shows a plan view of the companion plate.

Figure 6 is a detail illustration of a slightly modified form of construction of the top plate.

Referring more particularly to the drawings, 1 and 2 designate a bolt and nut re-

spectively, both of which may be of any desired construction, and 3 and 4 indicate two pieces of plate held together thereby.

The nut lock consists essentially of the top plate 5 and the companion plate 6 supplied with holes 14 and 15 respectively which are adapted to register with each other when the nut lock is assembled, for the passage of the bolt 1. Substantially centrally of the top plate 5 and integral therewith is a downwardly projecting transverse portion 7, the sides 8 of which are preferably bevelled and are adapted to fit within the correspondingly bevelled guides 9 in which the sides of the transverse groove 10 of the companion plate 6 terminate.

On the upper face of the top plate 5 a projection 11 is formed. This projection is so located that the side of the nut 2 will come in contact with the side of it when the nut has been screwed down into close proximity with the top plate. As the nut is tightened sufficient pressure can be exerted to depress the top plate 5 by flexing the extensions 16 of the companion plate 6, but on the other hand the projection effectively prevents the nut from slackening back by accidental rotation when the nut is subjected to vibration.

In the underside of the downwardly projecting transverse portion 7 keyways 12 may be supplied. In that case upwardly projecting guide pins or keys 13 should be arranged in the groove 10 to register with the said keyways. For particularly in nut locks of larger sizes I find the keys 13 and keyways 12 of assistance in assembling the parts.

Figure 6 shows a modification of the above described design. On the underside of the downwardly projecting portion 7 small projections 20 are formed. In that case depressions take the place of the keys 13 in the groove 10. In this way positive means of holding the top plate 5 and the companion plate 6 in correct relation to each other are provided.

The transverse groove 10 of the companion plate is formed within a centrally located depressed portion 21 of the stock and the sides of the groove which form the guides 9 extend upwardly and are there united to the inner ends of the flexed extensions 16 which project therefrom, and the outer ends of the said extensions are 110

flexed in the opposite direction, and are adapted to form bearing surfaces 17 against which the work, in the present case the plate 3, rests.

5 As the nut 2 is tightened the curvature of the flexed extensions 16 is flattened out, and therefore it is necessary to make the companion plate 6, and particularly the extensions 16, of a high grade of spring steel.

10 As the underside of the depressed portion 21 is materially lower than the inner ends of the extensions 16, the said depressed portion forms a stop and prevents the said extensions from being completely flattened out.

15 Referring now more particularly to Figures 3 and 4, it will be noted that I prefer to make the top plate 5 out of a blank as shown in Figure 3. The ends 7^a which are of lesser width than the central portion of

20 the top plate 5, are doubled under across the lines indicated at 19, so that the semi-circular openings 14^a each register with one side of the hole 14; and the edges 18, when the ends 7^a have been doubled under, are in close proximity to each other. Thus the downwardly projecting portion 7 may be formed, and the bevelled edges 8 and the keyways 12 shaped without the necessity of expending time and labor on machining, or having 30 to resort to heavy and complicated press work. Similarly the companion plate 6 can easily be stamped out in the form shown in Figure 5.

35 In the foregoing I have described the preferred embodiment of my invention, it is however understood that I may make alterations and modifications therein, pro-

vided the said alterations and modifications fall within the scope of what I claim.

Having thus described my invention what 40 I desire to secure by Letters Patent is:

1. A nut lock of the character described comprising a top plate having a hole therethrough and adapted to form a flat bearing surface for the underside of a nut, a projection adapted to prevent accidental rotation of a nut thereon, and a hole therethrough for the passage of a bolt, in combination with a companion plate having a hole registering with said first named hole, resilient 50 extensions adapted to exert upward pressure against the underside of the top plate, said plates being held in engagement one with the other by means of a projection on the underside of the top plate which cooperates with a groove in the top of the companion plate.

2. A nut lock as described in claim 1, wherein the underside of that portion of the companion plate in which the groove is 60 formed extends downwards and constitutes a stop to prevent the complete flattening of the resilient extensions.

3. A nut lock of the character described comprising a top plate having a hole therethrough, and a companion plate having flexed resilient extensions and a hole therethrough, in combination with means for slidably engaging the said plates one with the other transversely of their length, and means for locking the two plates one with the other when the aforesaid holes register with each other.

GEO. E. MONROE.
